UNITED STATES PATENT OFFICE.

ARTHUR KLEINFELDT, OF HOBOKEN, NEW JERSEY, ASSIGNOR OF ONE-HALF TO ARNOLD B. PERLA, OF BROOKLYN, NEW YORK.

PRESSURE-REGULATOR.

No. 911,505.

Specification of Letters Patent.

Patented Feb. 2, 1909.

Application filed March 14, 1908. Serial No. 421,019.

To all whom it may concern:

Be it known that I, ARTHUR KLEINFELDT, a citizen of the United States, residing in the city of Hoboken, in the State of New Jersey, have invented certain new and useful Improvements in Pressure-Regulators, of which the following is a specification, reference being had to the accompanying drawing, forming a part hereof.

10 This invention relates to the construction of pressure regulating or controlling devices and pressure indicating devices, such as are commonly employed in the handling of liquefied carbonic acid gas.

15 It has been proposed heretofore to combine both pressure regulating devices and pressure indicating devices in one structure, and to accomplish this result both of such devices have been arranged to be operated 20 from a single diaphragm which is subject to the pressure of the gas, the diaphragm being either positively connected to the two devices respectively or opposed by a spring for the purpose of closing the valve through 25 which gas is admitted. In either case the indicating devices and the regulating devices have not been sufficiently free in action to permit of such nicety in operation as is desirable.

30 One object of the present invention, therefore, is to so improve the construction of devices of this character as to secure the advantage of combining both regulating and indicating devices in one structure while permitting each to operate with the freedom 35 which is necessary to secure the desirable accuracy and sensitiveness of each.

Another object is to provide for a more positive closing of the inlet 40 valve, so that if the valve plug should be held from its seat, for example, by a particle of dust or dirt, the gas which passes will continue to act upon the mechanism to cause the valve plug to be pressed more firmly against the seat until the leakage is stopped.

45 A further object is to provide a construction in which only one gas chamber shall be required for the operation of both the indicating and regulating devices. Furthermore, 50 the arrangement of the parts is such that in their normal relations the inlet valve is closed and is held closed unless pressure is applied to the valve controlling means in opposition to the normal pressure thereon, such 55 pressure in opposition being applied prefer-

ably through a spring, the tension of which is capable of regulation by the operator.

The invention will be more fully explained hereinafter with reference to the accompanying drawing in which—

60 Figure 1 is a face view of the indicator, a portion of the gas controlling devices being shown in section. Fig. 2 is a view of the same in section on a plane at right angles to that of Fig. 1. Fig. 3 is a partial detail view 65 showing a slight modification.

65 In the construction represented in the drawing the gas is admitted to the improved indicating and regulating devices through a suitable connection *a*. The regulation head 70 *b*, with which the gas connection is established, has an inlet duct or channel *b'* which communicates with a valve port *b²*, a duct or channel *b³* from which the gas pressure is transmitted through a channel *b⁴* to the dia- 75 phragm chamber hereinafter referred to and from which gas is conducted through a duct or channel *b⁵*, to a valve chamber *b⁶*, from which the gas passes through a valve port *b⁷* and a duct or channel *b⁸* to the pipe which 80 may be connected to the regulating head at *b⁹* for the purpose of conducting the gas, under regulated pressure, to the place of use. The valve port *b⁷* is controlled, for the 85 purpose of cutting off altogether the flow of gas to the place of use, by a hand operated valve *c*, which may comprise a diaphragm *c'* held in place by a cap *c²* and a threaded stem *c³* provided with a hand wheel *c⁴*. The

regulating or diaphragm chamber *d*, to 90 which the pressure of the gas is transmitted, is formed by opposite diaphragms *d'* and *d²*, properly secured at their margins to an annular frame or casting which may and preferably does form an integral part of 95 what has been called the regulating head *b*. Such annular casting is properly secured within the casing *e* which supports the indicator dial *e'*. The diaphragm *d'* may act upon the indicator needle *e²* through any 100 suitable mechanism, that shown comprising the usual arrangement of lever *f*, quadrant *f'* and pinion *f²* on the staff *f³* which carries the indicator needle.

105 The diaphragm *d²*, which forms the other side of the common gas chamber *d*, but is free from the diaphragm *d'* and is not directly affected by its movements, controls the reducing valve through means which will now be described. Mounted upon a 110

fulcrum g , preferably near the margin of the diaphragm d^2 , is a lever g' which bears upon the diaphragm d^2 through the intermediary of an adjusting screw g^2 , which may be set before the casing e is applied, for the purpose of properly establishing or adjusting the relation of the lever g' to the diaphragm d^2 . The free end of the lever g' bears upon the free end of a cam lever h , and it may also be provided with a finger h' for the purpose of moving the lever h positively with the lever g' when the latter is moved as hereinafter described. The heel h^2 of the cam lever h rests upon a bearing plate h^3 which is adjustably supported by a set screw h^4 accessible from the outside of the casing. The set screw h^4 is carried in the end of a cap h^5 which is supported, as hereinafter described, by the regulating head b , being slotted at one side, as at h^6 , to permit the passage of the lever arm h . The lever h is in operative relation with a plunger h^7 , being preferably pivotally connected therewith, and the latter is arranged to control the admission of gas through the port b^2 . In order that escape of gas may be prevented without requiring packing of the plunger h^7 , a diaphragm i , of any suitable material, such as celluloid, is interposed between the plunger h^7 and the port b^2 , being tightly clamped, at its margin, against the seat provided therefor on the regulating head b by a cap i' through which the plunger h^7 passes and to which the cap h^5 is secured.

For the purpose of opposing with an adjustable pressure the outward movement of the diaphragm d^2 , under the varying pressure of gas in the gas chamber d , and thereby regulating the reducing valve, there is provided a spring k which bears against the lever g' in opposition to the diaphragm d^2 and is adjusted as to its tension by a screw k' mounted in a supplemental casing e^3 and provided with a hand wheel k^2 .

In describing the operation of the improved instrument, it may be assumed that all of the parts have been properly set or adjusted so that gas flows through the port b^2 at the predetermined pressure. It will be obvious that such gas as passes the port b^2 escapes through the channels b^3 , b^5 , b^6 (the port b^7 being open) and b^8 . The pressure of the gas transmitted through the channel or duct b^4 to the gas chamber d acts upon both diaphragms d' and d^2 , causing the pointer e^2 to perform its function of indicating the pressure and, so long as the pressure remains unchanged, causing the valve b^2 to be held open to the same extent. Should the pressure of gas admitted through the port b^2 increase ever so slightly, it will not only cause such increase of pressure to be indicated through the movement of the diaphragm d' , but, through the diaphragm d^2 , it will move the lever g' outward slightly,

and this movement of the lever g' , rocking the lever h upon its cam surface or eccentric will move the plunger h^7 slightly toward the port b^2 , thereby reducing the flow of gas through such port. Should a particle of dust or dirt lodge between the valve seat b^2 and the diaphragm i , the gas will continue to escape and to bulge the diaphragm d^2 further outward, thereby causing greater pressure to be exerted through the lever h until the particle is crushed or embedded in the diaphragm i so that the passage of gas is entirely prevented. Should the pressure of gas fall below the predetermined degree the diaphragm d^2 will be permitted to yield inwardly in response to the pressure of the spring k acting through the lever g' and the lever h will, through the finger h' , be caused to move in a direction to withdraw the plunger h^7 and thereby permit the port b^2 to be opened more widely. Through the adjusting screws g^2 , h^4 and k^2 the operation of the several working parts may be so controlled as to meet varying conditions or requirements or to compensate for wear. Through the operation of the valve e the flow of gas from the regulator may be cut off at any time. It will be obvious that although there is but a single gas chamber, the operation of each diaphragm is unaffected by the movement of the other (except, as it may be, momentarily) and the sensitiveness and accuracy of indication are therefore preserved together with the sensitiveness and accuracy of regulation.

In the modification shown in Fig. 3 the lever g' is shown as provided with a spring g^3 , which serves merely to hold the lever in engagement with its fulcrum g . In this modification the spring k and the adjusting screw k^2 , of the construction shown in Fig. 2, are omitted, and in place thereof the lever g' is provided with a light spring g^4 which has only power enough to overcome the friction of the lever h and its associated parts, and thereby open the valve port b^2 without offering resistance to the movement of the diaphragm d^2 . The adjusting screw g^2 of the construction shown in Fig. 2 is, in the construction shown in Fig. 3, extended through the shell or casing e , as shown at g^5 , and is provided with a hand wheel g^6 . It will be seen that in the operation of this form of the mechanism, the lever g' is held normally by the spring g^4 in such position as to cause the cam lever h to open the valve port b^2 and permit gas to enter. The adjusting screw g^5 is so set that when the desired pressure has been attained in the gas chamber d the diaphragm d^2 will then have been bulged sufficiently to make contact with the end of the screw g^5 and, through the lever g' , to rock the cam lever h and close the valve port b^2 . By adjusting the screw g^5 toward and from the diaphragm

the pressure required to operate the valve may be diminished or increased.

It will be obvious that various changes in details of construction and arrangement 5 may be made without departing from the spirit of the invention, which is not limited to the precise construction shown and described herein.

I claim as my invention:

- 10 1. In a combined pressure regulator and indicator, the combination of two diaphragms forming between them a common gas chamber, indicating mechanism in operative relation with one of said diaphragms 15 and external to said gas chamber, and valve mechanism to control the admission of gas to said chamber in operative relation with the other of said diaphragms or is subject to the action of the gas, whereby the pressure of 20 gas in said chamber actuates both the indicating mechanism and the valve mechanism and neither of said mechanisms is affected by the movements of the other or is subject to the action of the gas.
- 25 2. In a combined pressure regulator and indicator, the combination of an annular frame, diaphragms secured at opposite sides of said frame to form a gas chamber between them, indicating mechanism in operative 30 relation with one of said diaphragms and external to said gas chamber, and valve mechanism to control the admission of gas to the chamber between the diaphragms in operative relation with the other of said 35 diaphragms and external to said gas chamber, whereby the pressure of gas in said chamber actuates both the indicating mechanism and the valve mechanism and neither of said mechanisms is affected by the movements of the other or is subject to the action 40 of the gas.

3. The combination of a casing bearing an indicator dial, an annular frame supported within the casing, diaphragms secured to 45 said frame at opposite sides thereof, indicating mechanism in operative relation with one of said diaphragms and valve mechanism to control the admission of gas to the chamber between the diaphragms in operative 50 relation with the other of said diaphragms.

4. In a pressure regulator, the combination of a gas chamber, a diaphragm forming one side of said gas chamber, a valve port and connections to admit gas pressure to 55 said chamber, a valve and valve lever to close said port, and a lever acted upon by said diaphragm but independent thereof and bearing against the valve lever to operate the same, said levers being external to the gas 60 chamber.

5. In a pressure regulator, the combination of a gas chamber, a diaphragm forming one side of said gas chamber, a valve port and connections to admit gas pressure to 65 said chamber, a valve and valve lever to

close said port, and a lever acted upon by said diaphragm but independent thereof and bearing against the valve lever to operate the same, said levers being external to the gas chamber, the last named lever having a 70 finger to engage the valve lever to move the same positively in a direction to open the valve.

6. In a pressure regulator, the combination of a gas chamber, a diaphragm forming 75 one side of said gas chamber, a valve port and connections to admit gas pressure to said chamber, a valve and valve mechanism to control said port, a lever acted upon by the diaphragm to operate said valve mechanism to close the valve and independent of 80 said diaphragm, said lever and valve mechanism being external to the gas chamber, and a spring opposing the movement of the lever under the action of the diaphragm and 85 acting to open the valve.

7. In a pressure regulator, the combination of a gas chamber, a diaphragm forming one side of said gas chamber, a valve port and connections to admit gas pressure to 90 said chamber, a valve and valve mechanism to control said port, a lever acted upon by the diaphragm to operate said valve mechanism to close the valve and independent of 95 said diaphragm, said lever and valve mechanism being external to the gas chamber, and a spring opposing the movement of the lever under the action of the diaphragm and 100 acting to open the valve and means to adjust the tension of said spring.

8. In a pressure regulator, the combination of a gas chamber, a diaphragm forming one side of said gas chamber, a valve port and connections to admit gas pressure to said chamber, a plunger movable toward 105 and from said gas port to regulate the passage of gas therethrough, a cam lever coöperating with said plunger, a bearing surface for said cam lever, and means to actuate said lever through the movements of the diaphragm, said lever and means being external 110 to the gas chamber.

9. In a pressure regulator, the combination of a gas chamber, a diaphragm forming one side of said gas chamber, a valve port and connections to admit gas pressure to said chamber, a plunger movable toward and from said gas port to regulate the passage of gas therethrough, a cam lever coöperating with said plunger, a bearing surface for said cam lever, means to adjust the position of 115 said bearing surface with respect to the valve port and means to actuate said lever through the movements of the diaphragm.

10. In a pressure regulator, the combination of a gas chamber, a diaphragm forming one side of said gas chamber, a valve port and connections to admit gas pressure to said chamber, a valve diaphragm movable toward 120 and from said gas port to regulate the 130

passage of gas therethrough and means actuated by the diaphragm of the gas chamber to press the second named or valve diaphragm against the valve port.

- 5 11. In a pressure regulator, the combination of a gas chamber, a diaphragm forming one side of said gas chamber, a valve port and connections to admit gas pressure to said chamber, a valve diaphragm to coöperate
10 with said gas port, a cap to secure said valve diaphragm in place, a plunger to coöperate with said valve diaphragm, a cam lever to

actuate the plunger, a bearing plate for the cam lever supported from said cap and means whereby the cam lever is actuated 15 through the movements of the first named diaphragm.

This specification signed and witnessed this 11th day of March, A. D., 1908.

ARTHUR KLEINFELDT.
